UNITED STATES PATENT OFFICE.

JOSEPH SAM'L. BEEMAN, OF LONDON, ENGLAND.

CIGARETTE-MOUTHPIECE-APPLYING MACHINE.

SPECIFICATION forming part of Letters Patent No. 739,376, dated September 22, 1903.

Application filed March 27, 1902. Serial No. 100,246. (No model.)

To all whom it may concern:

Be it known that I, JOSEPH SAMUEL BEEMAN, a subject of the King of England, residing at London, England, have invented 5 certain new and useful Improvements in or Relating to Cigarette-Mouthpiece-Applying Machines, of which the following is a specification.

This invention relates to improvements in 10 cigarette-mouthpiece-applying machines, and has particular reference to machines in which cork paper, metal leaf, or like material is applied as a tip to the end of a cigarette.

Machines according to this invention are 15 specially adapted for the employment of a continuous strip of the mouthpiece-forming material, such strip preferably consisting of gold or other metal covered paper or paper with a cork or tobacco-leaf covering. It is, 20 however, to be understood that any suitable material may be used. This strip is supplied with an adhesive material, which may be in a dry form on the strip and may be moistened during the operation of the machine or may 25 be applied wet to the strip in any convenient way. The strip is led to a retainer or device to which it temporarily adheres, and a portion sufficient for one mouthpiece is severed from the strip and automatically brought 30 into contact with the cigarette to be tipped and rolled around it, a guide being provided to keep the strip straight during its application.

In the accompanying drawings, which illustrate one construction of cigarette-mouthpiece-applying machine according to this invention, Figure 1 is a plan. Fig. 2 is a side elevation; Fig. 3, a similar view with the mechanism in another position; Fig. 4, a perspective view, and Fig. 5 a diagram showing a portion of the machine in side elevation with the parts in a different position from that shown in Figs. 2 and 3.

Like letters indicate like parts throughout 45 the drawings, and in some of the figures certain parts are removed for the sake of clearness.

Upon a rigid base A are standards A' A² to 50 A¹⁰, serving to support the various parts of the machine. A hopper B is mounted on the standards A⁵ and A⁶ to contain the cigarettes to be tipped; but details of this hopper are

not shown, as they form no part of the present invention. From the hopper B the cigarettes pass one by one to a trough or channel 55 B', mounted in line with a plunger C, which is reciprocated in and out of the trough B'. This plunger is mounted on a block C', free to slide on guide-bar C², held between the standards A' and A⁵, and is reciprocated 60 through the action of a pivoted arm C³, a lever C⁴, and a cam C⁵, the cam being driven from the main shaft D of the machine. Power is supplied to the main shaft D from a pulley D² through a clutch D'.

Mounted in line with the trough B' is a holder E, adapted to grip the cigarette sufficiently tightly to rotate it while it is being tipped, but not tightly enough to prevent its removal after tipping by being pushed out of 70 the holder by the succeeding cigarette. This holder E is provided with a pinion E', the teeth of which engage with the teeth of a segment-like rack E², mounted on the flange of a disk E³ on the main shaft D, so that the 75 holder E is intermittently rotated. A small friction or brake wheel E⁴ is provided on the holder E and a spring E⁵ arranged to bear upon it, so that accidental rotation of the holder E is avoided.

The standards A⁹ A¹⁰ are connected by a curved bar A¹¹, a bar A¹², and guide-bars A¹³ and A¹⁴. Mounted with freedom to slide upon the guide-bars A¹³ and A¹⁴ is a frame F, carrying a retainer G, which can be turned 80 about a stud G'. This frame F is connected through a stud and pin F' to a slotted lever F², pivoted to the standard A⁸ and provided with a roller F³, engaging with a cam-groove F⁴ on the back of the disk E³. By this mechanism the frame F is reciprocated, as herein-after described.

The retainer G is furnished with a squared portion G² and is kept from accidental rotation by a bar H, pivoted to the bar A¹² and 95 pressed down by a spring H', mounted on the standard A¹⁰. At the back of the retainer are four projections or teeth G³, Fig. 2, with inclined faces, and as the retainer is carried by the frame F in a forward direction—i. e., from left to right, as shown in Fig. 2—one of these projections is brought into contact with the end of a pivoted arm J, mounted on the back 100 of the bar A¹², and the retainer forced around

against the action of the spring-controlled bar H, a recess (shown in dotted lines in Fig. 3) in the bar A¹² permitting and completing this turning movement. After the retainer 5 has been turned the bar H comes down on the succeeding face of the squared portion G² and keeps the retainer from further rotation until it is next operated by the arm J. This arm is pressed down by a spring J', and when 10 the retainer passes toward the holder E the arm is lifted on the inclined face of the top-most projection G³, so that the retainer passes under the arm J without being rotated. A pin J² on the arm J enters a slight recess in 15 the bar A¹² and prevents that arm from descending for more than the required distance. A continuous strip of tipping material K in the form of a roll is supported as at K', Figs. 2 and 4, and it is convenient to employ a strip 20 which has been previously coated with a suitable adhesive. The strip is moistened by causing it to pass over a pad K², kept moist by liquid from a tank K³, and is then led over and between guides K⁴ onto the retainer G, 25 being further guided by flanged projections G⁴ on that member. To keep the strip K in contact with the retainer and prevent its displacement, a presser-roller K⁵, mounted on a spring-controlled pivoted arm K⁶, the position of which may be adjusted by a cam K⁷, is employed. A guard-plate K⁸ is fixed to the frame F so as to leave only a narrow opening 30 between its face and the adjacent portion of the retainer, and through this space the strip K passes.

Mounted on a bracket on the standard A¹⁰ is a knife L, and when the retainer G, carrying the strip K, is near the end of its forward stroke the strip is forced over the cutting 40 edge of the knife and a portion sufficient for one mouthpiece is severed from it. In order that the knife may not drag the strip and displace it from the retainer, a projecting bar L' is arranged so that it presses upon the strip K and clamps it against the retainer just above the place where the severance is effected. This clamping or pressing bar L' is mounted upon a support L², which can, like the frame F, slide upon the guide-bars 45 A¹³ and A¹⁴, and it is connected to the frame F through a spring L³, a stop L⁴ being provided on the guide-bar A¹³ to prevent the support L² traveling back beyond the desired limit. The support L² is furnished with a 50 roller L⁵, which engages with a cam L⁶ on the front face of the disk E³. This cam L⁶ as it rotates moves the support L² and the parts mounted on it when the roller is in contact with the cam; but when the frame F is in 55 the forward part of its travel—as, for example, in the position shown in Fig. 3—the retainer G on the frame F is in contact with the clamping-bar L' and presses the support L² forward against the action of the spring 60 L³. Thus it will be seen that the movements of the frame F and the support L² vary rela-

tively on account of the independent action of the cam L⁶.

Between the flanged projections G¹ on the retainer G are gaps G⁵, three of which are 70 bridged over by the strip K when the machine is in the position shown in Fig. 3. Slots G⁶ are formed in the projections themselves, and it is through one of these slots G⁶ that the knife L enters when severing the 75 strip. The presser-roller K⁵ is arranged so that it presses the strip K against the edges of the slot G⁶, which happens to be at the bottom of the retainer, and a firmer grip of the strip on the retainer is thus secured. To 80 lift the front part of the severed portion of the strip ready for application to the cigarette, a lifting device in the form of a pivoted lever M is employed. This lever is pivoted to the frame F and has a projecting arm 85 M', adapted to pass in and out of the gaps G⁵ when the lever M is turned about its pivot. This turning action is brought about by means of a pivoted cam M², swinging freely in one direction about its pivot on the lever M, but 90 prevented from moving in the other direction by a pin M³. The cam is brought into contact with a fixed table M⁴ by the reciprocation of the frame F. When out of contact with the table, as in Fig. 3, or when moving 95 forward—i. e., from left to right—the cam is inoperative and the lever M lies within the retainer G; but when the frame F moves backward toward the holder while the cam M² is in contact with the table M⁴ the lever 100 M is lifted against the action of a spring M⁵ up through one of the gaps G⁵, carrying the front part of the severed portion of the strip K with it, so that its under surface is ready for application to the end of the cigarette. 105 This position of the strip and lifting device is clearly shown in Fig. 2. A guard N is mounted upon the support L² to prevent the strip when lifted by the lever M from bending back too far, and thus becoming displaced. To attach the front end of the strip to the cigarette and to finally secure the strip when rolled up, a tipping device in the form 110 of a counterbalanced lever O is used. This lever is pivoted to the bar A¹¹ and is provided 115 with an adjustable screw O', which rests on the circumference of the disk E³, that circumference being provided with cam projections O² O³ O⁴ in the path of the screw O', so that the lever O rises and falls at predetermined intervals. It is found convenient in some cases to heat the tapper O in order to cause the adhesion of the strip and the cigarette to take place more quickly, and for this purpose a side plate or wing O⁵ is attached 120 to the end of the lever O adjacent to the cigarette and may be heated by a gas-flame or other convenient means, as shown in Fig. 2. In order that the severed portion of the strip may be properly applied to the end 125 of the cigarette, a guide is provided for it. A convenient form of this guide is shown 130

in the drawings and comprises a tube P, axially in line with the holder E and having an opening P' of a width approximately equal to that of the strip K. By means of this guide 5 the sides of the strip are kept straight as it is rolled around the end of the cigarette. To insure that the tips shall always be applied in the same position relatively to the cigarette notwithstanding any slight variation in the 10 length of the cigarettes, it is arranged that each cigarette shall be primarily protruded too far through the holder E and then pushed back until a definite length remains beyond the holder. This adjustment is accomplished 15 by a stop-lever R, Figs. 2 and 4, mounted upon a bracket R', attached to the bar A¹¹. This lever R is controlled by a spring R², which tends to keep the lower end of the lever away from the cigarette S in the holder E. 20 The other end of the lever R projects beyond the bar A¹¹ and is operated upon by one end of a bell-crank lever R³, pivoted, as at R⁴, to the back of the bar A¹¹ and adapted at its lower end to engage with a cam projection R⁵, mounted in the path of the lever R³ upon the periphery of the disk E³. As the main shaft rotates the cam R⁵ comes into contact with the lever R³ and causes the end adjacent to the lever R to rise until it is stopped by an 25 adjustable screw R⁶. It will be seen that by this mechanism the lower end of the lever R is brought into a definite position relatively to the end of the cigarette, and the small projection or stop at the end of the lever actually 30 presses the cigarette back through the guide P and holder E until a definite length protrudes through the holder. The connection between the lever R³ and the stop-lever R is made by means of a spring R⁷, the elasticity 35 of which will enable the lever R³ to rise still further after the movement of the stop-lever R has been arrested by the adjusting-screw R⁶; so that an extremely fine adjustment of the two levers and the screw is not necessary. 40

45 The operation of the machine is as follows, starting from the position illustrated in Fig. 3: In the figure mentioned the retainer is shown at the end of its forward stroke, the knife L having entered and severed the strip K upon the retainer G, and the severed portion lies over the top right-hand gap G⁵, having the arm M' of the lifting device M beneath it. It is to be noted that the rear part of the severed portion of the strip is gripped 50 by the clamping-bar L', which has been forced forward against the action of the spring L³ by the retainer G. The rotation of the main shaft D in the direction of the arrow in Fig. 3 causes the frame F, carrying the retainer, 55 to commence its backward stroke—i. e., toward the holder E. As it moves backward the retainer lifts the lever J against the action of its spring J' and presently the pivoted cam M² comes into contact with the fixed 60 table M⁴. As the cam cannot turn, owing to the position of the pin M³, the lever M is lifted, and its upper end, bearing the arm M',

emerges from the gap G⁵, carrying the front part of the severed portion of the strip with it, the rear part of that portion being still 70 clamped by the bar L', which under the action of the spring L³ has followed up the movement of the frame F and retainer G. The guard N prevents the front part of the strip from doubling back on itself when raised 75 by the lever M, and the whole mechanism—retainer, guard, and lifting device—now closely approaches the end of the cigarette in the holder E, as shown in Fig. 2. The clamping-bar L' is still in close contact with 80 the strip on the adjacent portion of the retainer, the portion of the frame L² which slides upon the guide-bar A¹³ having almost, but not quite, come into contact with the stop L⁴. It will be seen on reference to Fig. 2 85 that the tapper O is raised by the cam O², but is approaching the abrupt fall in that cam, and it will also be apparent that the cam R⁵, operating the push-back lever R, has just been in operation, so that the cigarette S in 90 the holder has been pushed back into the exact position for the application of the strip. A slight further rotation of the main shaft now causes the tapper O to fall and press the front end of the severed portion of the strip 95 into contact with the end of the cigarette which is accessible through the opening P' in the guide P. Two small auxiliary cam projections O⁴ are conveniently provided, although they may be dispensed with. These 100 lift the tapper and cause it to give two slight blows to the strip instead of remaining continuously upon it. It will be noticed that, as shown in Fig. 2, the portion of the cam-groove F⁴ just coming into operation is practically 105 semicircular. Hence the retainer will for the next half-revolution or thereabouts stay in the position indicated. There is, however, a slight diversion in the cam-groove, as indicated at F⁵, and the object of this diversion is 110 to momentarily bring the frame F forward so that the cam M² comes over the edge of the table M⁴ and the lever M falls through the gap G⁵ into the retainer, leaving the severed portion of the strip attached to the cigarette. 115 As soon as the rack E² comes into engagement with the teeth of the pinion E⁷ the holder and cigarette are rotated, and the position of the rack, pinion, and tapper when this occurs is shown diagrammatically in Fig. 120 5, where it will be noticed that the tapper O is slightly lifted by the cam projection O³, so that it is out of contact with the strip and allows it to roll up freely under the influence of the guide P. The tapper remains in this raised 125 position until the severed portion of the strip has been rolled around the end of the cigarette, when the tapper comes down upon it and causes the rear end to adhere closely to the portion underneath it. 130

It is sometimes found convenient to give a final slight tap to the cigarette, and for this purpose another small cam projection O⁴, similar to those previously mentioned, is provided

slightly behind the projection O^3 . It should be mentioned that just before this rotation of the cigarette takes place the cam L^6 comes into contact with the roller L^5 on the support 5 L^2 and causes that support, with the guard N and clamping bar L' , to commence their forward stroke, leaving the severed portion of the strip on the retainer G . The retainer G now commences its next forward stroke, and 10 the uppermost projection G^3 coming into contact with the end of the lever J the retainer is forced around until the succeeding face of the squared portion G^2 is controlled by the bar H . The partial rotation of the retainer G 15 brings a fresh portion of the strip K into the right position for severance, and the retainer, proceeding on its forward stroke, comes into contact with the clamping-bar L' and then brings the strip over the knife, the general 20 position of the mechanism being that taken for the starting-point—viz., the position illustrated in Fig. 3.

In the above description the ejection of the finished cigarette has not been described; but 25 it occurs through the action of the cam C^5 upon the plunger C at about the same time as the tapper O is first raised by the projection O^2 —that is to say, when the parts of the machine are in a position somewhat before 30 that illustrated in Fig. 2. The plunger pushes a fresh cigarette out of the trough B' through the holder E and pushes it too far through that holder, the adjustment of the cigarette in the holder taking place, as mentioned above, through the action of the cam R^5 , lever R^3 , and stop-lever R . As the mechanism is arranged in the particular machine illustrated, the finished cigarette is ejected by the one which succeeds it in the holder E ; 35 but this arrangement is not essential to the carrying out of the invention, for by suitably proportioning the cam and other mechanism operating the plunger that member can be made to eject the finished cigarette directly 40 and then return and push the fresh cigarette 45 and then return and push the fresh cigarette into the holder ready for tipping.

As above mentioned, it is found convenient to employ a strip of tipping material which has been previously coated with a suitable adhesive and allowed to dry, the strip being then rolled up and taken to the retainer, passing over the moistened pad on its way. Preferably the moistening fluid is slightly warmed, and in Fig. 2 a jet K^9 is 50 shown diagrammatically in a position to heat the contents of the tank K^8 . Obviously, however, the strip K might not be coated to start with and might be supplied with the requisite amount of adhesive supplied in a fluid 55 form to the pad K^2 or to any other convenient moistening device. It is found desirable in practice before starting the machine to apply a little moisture to the surface of the retainer where it comes in contact with the 60 strip; but as soon as the machine is in operation it is found that the strip itself brings sufficient moisture with it. Again, although it 65

is preferred to employ a guide P having parts which operate upon both sides of the strip as it is applied to the cigarette the fixed 70 guide for the outer side of the strip might be dispensed with; but in this case it would be advisable to arrange the push-back stop-lever R so that it remained in contact with the end of the cigarette while it was being tipped, 75 acting itself as a guide for the adjacent side of the strip, the opposite side of the strip being guided by a fixed guide or by the projecting end of the holder.

Although the spring-controlled presser- 80 roller K^5 is sometimes advantageous, it may be dispensed with, say, when dealing with a strip of material—such, for instance, as gold-covered paper—it being found that such a strip will adhere sufficiently to the retainer 85 without the pressure exercised by the roller.

A retainer such as that illustrated, having a squared portion at its back and furnished with four projections, is convenient; but it will be understood that other similar 90 arrangements may be used. For instance, the size of the retainer might be increased and six sets of projections G^4 arranged around its periphery, a hexagonal rear portion being provided to keep the retainer in the desired 95 position.

What I claim as my invention, and desire to secure by Letters Patent, is—

1. In a cigarette-mouthpiece-applying machine, the combination of an axially-rotatable 100 tube forming a holder for the cigarette and through which from end to end the cigarette is passed, a retaining-support for the end of a continuous strip of mouthpiece-forming material, means for moistening the strip, means 105 for severing from the strip a portion sufficient for one mouthpiece and means for bringing the severed portion into contact with the cigarette.

2. In a cigarette-mouthpiece-applying machine, the combination of a holder for the cigarette, a retaining-support for the end of a continuous strip of mouthpiece-forming material, means for moistening the strip, means 115 for severing from the strip a portion sufficient for one mouthpiece and a lifting device to partially disengage the severed portion of the strip from the retaining-support and prepare it for contact with the cigarette.

3. In a cigarette-mouthpiece-applying machine, the combination of a holder for the cigarette, a retaining-support for the end of a continuous strip of mouthpiece-forming material, means for moistening the strip, means 120 for guiding the strip into contact with the retaining-support, means for severing from the strip a portion sufficient for one mouthpiece and a lifting device to partially disengage the severed portion of the strip from the retaining-support and prepare it for contact with the cigarette.

4. In a cigarette-mouthpiece-applying machine, the combination of a holder for the cigarette, a retaining-support for the end of a

continuous strip of mouthpiece-forming material, means for moistening the strip, means for guiding the strip into contact with the retaining-support, means for severing from the strip a portion sufficient for one mouthpiece, means for moving the retaining-support and the severed portion into proximity with the cigarette and a lifting device to partially disengage the severed portion of the strip from the retaining-support and prepare it for contact with the cigarette.

5 5. In a cigarette-mouthpiece-applying machine, the combination of a holder for the cigarette, a retaining-support for the end of a continuous strip of mouthpiece-forming material, means for moistening the strip, means for guiding the strip into contact with the retaining-support, means for severing from the strip a portion sufficient for one mouthpiece, a device to keep the severed portion on the retaining-support, means for moving the retaining-support and the severed portion into proximity with the cigarette and a lifting device to partially disengage the severed portion of the strip from the retaining-support and prepare it for contact with the cigarette.

10 6. In a cigarette-mouthpiece-applying machine, the combination of a holder for the cigarette, a retaining-support for the end of a continuous strip of mouthpiece-forming material, means for moistening the strip, means for guiding the strip into contact with the retaining-support, means for severing from the strip a portion sufficient for one mouthpiece, a device to keep the severed portion on the retaining-support, means for moving the retaining-support and the severed portion into proximity with the cigarette, a lifting device to partially disengage the severed portion of the strip from the retaining-support and prepare it for contact with the cigarette and a guide for the severed portion.

15 7. In a cigarette-mouthpiece-applying machine, the combination of a holder for the cigarette, a retaining-support for the end of a continuous strip of mouthpiece-forming material, means for moistening the strip, means for guiding the strip into contact with the retaining-support, means for severing from the strip a portion sufficient for one mouthpiece, a device to keep the severed portion on the retaining-support, means for moving the retaining-support and the severed portion into proximity with the cigarette, a lifting device to partially disengage the severed portion of the strip from the retaining-support and prepare it for contact with the cigarette, a guard to keep the lifted part in its proper position and a guide for the severed portion.

20 8. In a cigarette-mouthpiece-applying machine, the combination of a holder for the cigarette, a retaining-support for the end of a continuous strip of mouthpiece-forming material, means for moistening the strip, means for guiding the strip into contact with the retaining-support, means for severing from the strip a portion sufficient for one mouthpiece, a de-

vice to keep the severed portion on the retaining-support, means for moving the retaining-support and the severed portion into proximity with the cigarette, a lifting device to partially disengage the severed portion from the retaining-support and prepare it for contact with the cigarette, a guard to keep the lifted part in its proper position, a guide for the severed portion and means for securing the adhesion of the severed portion to the cigarette.

25 9. In a cigarette-mouthpiece-applying machine, the combination of a holder for the cigarette, means for protruding the cigarette too far through the holder and for partially returning it into the holder, a retaining-support for the end of a continuous strip of mouthpiece-forming material, means for moistening the strip, means for guiding the strip and for holding it in contact with the retaining-support, means for severing from the strip a portion sufficient for one mouthpiece, a device to keep the severed portion on the retaining-support, means for moving the retaining-support and the severed portion into proximity with the cigarette, a lifting device to partially disengage the severed portion from the retaining-support and prepare it for contact with the cigarette, a guard to keep the lifted part in its proper position, a guide for the severed portion and means for securing the adhesion of the severed portion to the cigarette.

30 10. In a cigarette-mouthpiece-applying machine, the combination of a holder for the cigarette, means for intermittently rotating the holder, a retaining-support for the end of a continuous strip, said strip being coated with an adhesive material, a moistened pad over which the strip is drawn, means for intermittently reciprocating and rotating the retaining-support, a knife against which the strip is carried by the retaining-support to sever a portion sufficient for one mouthpiece, a lifting device to partially disengage the severed portion from the retaining-support and bring its under surface into position for contact with the cigarette and a pivoted cam operating to raise the lifting device substantially as set forth.

35 11. In a cigarette-mouthpiece-applying machine, the combination of a holder for the cigarette, means for intermittently rotating the holder, a retaining-support for the end of a continuous strip, said strip being coated with an adhesive material, a moistened pad over which the strip is drawn, means for intermittently reciprocating and rotating the retaining-support, guides to lead the strip into contact with the retaining-support, a knife against which the strip is carried by the retaining-support to sever a portion sufficient for one mouthpiece, a lifting device to partially disengage the severed portion from the retaining-support and bring its under surface into position for contact with the cigarette and a pivoted cam operating to raise the lifting device substantially as set forth.

12. In a cigarette-mouthpiece-applying machine, the combination of a holder for the cigarette, means for intermittently rotating the holder, a retaining-support for the end of a continuous strip, said strip being coated with an adhesive material, a moistened pad over which the strip is drawn, means for intermittently reciprocating and rotating the retaining-support, guides to lead the strip into contact with the retaining-support, a knife against which the strip is carried by the retaining-support to sever a portion sufficient for one mouthpiece, a lifting device to partially disengage the severed portion from the retaining-support and bring its under surface into position for contact with the cigarette a pivoted cam operating to raise the lifting device and a guide to keep the strip straight as it is rolled around the cigarette substantially as set forth.
13. In a cigarette-mouthpiece-applying machine, the combination of a holder for the cigarette, means for intermittently rotating the holder, a retaining-support for the end of a continuous strip, said strip being coated with an adhesive material, a moistened pad over which the strip is drawn, means for intermittently reciprocating and rotating the retaining-support, guides to lead the strip into contact with the retaining-support, a knife against which the strip is carried by the retaining-support to sever a portion sufficient for one mouthpiece, a spring-controlled clamp to keep the severed portion on the retaining-support, a lifting device to partially disengage the severed portion from the retaining-support and bring its under surface into position for contact with the cigarette, a pivoted cam operating to raise the lifting device, a guard to keep the lifted portion in its proper position, a guide to keep the strip straight as it is rolled around the cigarette, a tapping device to secure the adhesion of the severed portion of the cigarette and means for operating such device substantially as set forth.
14. In a cigarette-mouthpiece-applying machine the combination of a holder for the cigarette, means for intermittently rotating the holder, a retaining-support for the end of a continuous strip, said strip being coated with an adhesive material, a moistening-pad over which the strip is drawn, means for intermittently reciprocating and rotating the retaining-support, guides to lead the strip into contact with the retaining-support, a knife against which the strip is carried by the retaining-support to sever a portion sufficient for one mouthpiece, a spring-controlled clamp to keep the severed portion on the retaining-support, a lifting device to partially disengage the severed portion from the retaining-support and bring its under surface into position for contact with the cigarette, a pivoted cam operating to raise the lifting device, a guard to keep the lifted portion in its proper position, a guide to keep the strip straight as it is rolled around the cigarette, a tapping device to secure the adhesion of the severed portion of the cigarette and means for operating such device substantially as set forth.
15. In a cigarette-mouthpiece-applying machine the combination of a holder for the cigarette, means for intermittently rotating the holder, a retaining-support for the end of a continuous strip, said strip being coated with an adhesive material, a moistened pad over which the strip is drawn, means for intermittently reciprocating and rotating the retaining-support, guides to lead the strip into contact with the retaining-support, a knife against which the strip is carried by the retaining-support to sever a portion sufficient for one mouthpiece, a plunger for protruding the cigarette too far through the holder, means for operating the plunger, a pivoted stop-lever for partially returning the cigarette into the holder, means for bringing the stop-lever into a definite position relatively to the holder, a retaining-support for the end of a continuous strip, said strip being coated with an adhesive material, a moistening-pad over which the strip is drawn, means for intermittently reciprocating and rotating the retaining-support, guides to lead the strip into contact with the retaining-support, a knife against which the strip is carried by the retaining-support to sever a portion sufficient for one mouthpiece, a spring-controlled clamp to keep the severed portion on the retaining-support, a lifting device to partially disengage the severed portion from the retaining-support and bring its under surface into position for contact with the cigarette, a pivoted cam operating to raise the lifting device, a guard to keep the lifted portion in its proper position, a guide to keep the strip straight as it is rolled around the cigarette, a tapping device to secure the adhesion of the severed portion of the cigarette and means for operating such device substantially as set forth.
16. In a cigarette-mouthpiece-applying machine the combination of a holder for the cigarette, means for intermittently rotating the holder, a plunger for protruding the cigarette too far through the holder, means for operating the plunger, a pivoted stop-lever for partially returning the cigarette into the holder, means for bringing the stop-lever into a definite position relatively to the holder, a retaining-support for the end of a continuous strip, said strip being coated with an adhesive material, a moistening-pad over which the strip is drawn, means for intermittently reciprocating and rotating the retaining-support, guides to lead the strip into contact with the retaining-support, a knife against which the strip is carried by the retaining-support to sever a portion sufficient for one mouthpiece, a spring-controlled clamp to keep the severed portion on the retaining-support, a lifting device to partially disengage the severed portion from the retaining-support and bring its under surface into position for contact with the cigarette, a pivoted cam operating to raise the lifting device, a guard to keep the lifted portion in its proper position, a guide to keep the strip straight as it is rolled around the cigarette, a tapping device to secure the adhesion of the severed portion of the cigarette and means for operating such device substantially as set forth.
17. In a cigarette-mouthpiece-applying machine the combination of a holder for the cigarette, means for intermittently rotating the holder, a plunger for protruding the cigarette too far through the holder, means for operating the plunger, a pivoted stop-lever for partially returning the cigarette into the holder, means for bringing the stop-lever into a definite position relatively to the holder, a retaining-support for the end of a continuous strip, said strip being coated with an adhesive material, a moistening-pad over which

the strip is drawn, means for intermittently reciprocating and rotating the retaining-support, guides to lead the strip into contact with the retaining-support, a knife against which the strip is carried by the retaining-support to sever a portion sufficient for one mouthpiece, a spring-controlled clamp to keep the severed portion on the retaining-support, a lifting device to partially disengage the severed portion from the retaining-support and bring its under surface into position for contact with the cigarette, a pivoted cam operating to raise the lifting device, a guard to keep the lifted portion in its proper position, a guide to keep the strip straight as it is rolled around the cigarette, a heated tapping device to secure the adhesion of the severed portion

of the cigarette and means for operating such device substantially as set forth.

18. In a cigarette-mouthpiece-applying machine, the combination with a rotating holder for the cigarette, of a guide axially in line with the holder having an opening approximately of the same width as the strip to be applied to the cigarette and serving to keep that strip straight substantially as set forth.

In testimony whereof I have signed my name to this specification in the presence of two subscribing witnesses.

JOS. SAM'L. BEEMAN.
